UNITED STATES PATENT OFFICE.

JOHN GRIFFIN, OF WHITE PLAINS, NEW YORK.

COMBINED AIR AND WATER CRAFT.

Application filed August 5, 1927. Serial No. 210,900.

The present disclosure of the invention relates to a craft which without alteration in construction may be used for travel in the air, on the surface of water, or below the surface 5 of the water. It is to be understood however, that a number of features of construction herein embodied, may be employed either in an aircraft or a water-craft and hence they are not restricted to use in a combined air 10 and water craft.

It is the principal object of the invention to provide a craft which embodies unique propelling means to act against either air or water to propel the ship, said propelling 15 means embodying weight-sustaining means for the craft when the latter is used in the air.

A further object is to provide unique means for mounting and adjusting the propelling means so that the latter may be made to cause 20 ascent or descent of the craft and may also be made to effect steering thereof.

A still further aim is to provide means for so adjusting the propelling means with respect to the body of the ship, as to effect sub- 25 merging of the latter in water when desired.

With the foregoing and minor objects in view, the invention resides in the novel subject matter hereinafter described and claimed, the description being supplemented by the 30 accompanying drawings.

Fig. 1 is a side elevation showing the craft conditioned for use as an airship.

Fig. 2 is a view similar to Fig. 1, parts 35 however being broken away and in section.

Fig. 3 is a top plan view partly in horizontal section.

Figs. 4 and 5 are respectively transverse and longitudinal sections on the correspondingly numbered lines of Fig. 3.

Fig. 6 is a fragmentary side elevation 40 showing the craft conditioned for use in water.

In the drawings above briefly described, 6 denotes a combined fuselage and hull, whose 45 cockpit 7 may have a suitable water-tight dome or closure 8 to exclude water when the hull is submerged.

Opposite sides of the member 6 are provided with axially aligned transverse bearings 50 9 through which outer tubular shafts 10 pass rotatably, stuffing boxes 11 being provided around said shafts at the outer ends of said bearings. Passing rotatably through the shafts 10, is a shaft 12 having cranks 13 at 55 opposite sides of the member 6. By means of

a suitable transmission mechanism 14, the shaft 12 is driven from a motor 15.

Stuffing boxes 16 are provided around the shaft 12 at the outer ends of the shafts 10, and these shafts 10 are rigidly joined to a pair of longitudinal rods 17 which may be swung into different angular relations with the body member 6, by rotating said shafts 10. For so turning these shafts, I prefer to provide them with independent worm gears 18 meshing with worms 19 on two control shafts 20 extending rearwardly and provided with hand wheels 21 in front of the seat 22 for the pilot.

At opposite sides of the body 6, elongated 70 downwardly-cupped weight-sustaining and propelling members 23 are disposed, said members having bearings 24 through which the cranks 13 pass. These bearings are disposed between the ends of the members 23 75 and at their rear ends, the latter are pivotally and slidably connected with the rods 17. To establish this pivotal and slideable connection, a bearing 25 is provided slideable along the rod 17 and itself having a transverse 80 bearing 26 in which one end of a short transverse shaft 27 is turnably received, the outer end of this shaft being provided with lugs 28 suitably secured to a transverse rod or the like 29 at the rear end of the member 23. As 85 the crank shaft 12 is driven, the members 23 are moved forwardly, downwardly, rearwardly and upwardly by means of the cranks 13 and during these movements, the bearings 25 slide back and forth upon the rods 17 and the 90 shafts 27 turn in the bearings 26. By turning the hand wheels 21 as may be required, the shafts 10 may be turned, thus vertically swinging the rods 17 to dispose the members 23 at any desired angular relation or relations 95 with respect to the body 6. By means of these hand wheels 21, the members 23 may be so adjusted as to cause ascent of the ship, descent thereof, lateral stabilizing, and steering.

The craft will operate equally as well in 100 water as it will in the air, the members 23 then acting upon the water to propel the ship. If these members be inverted as shown in Fig. 6, by sufficient rotation of the hand wheels 21, they will act as means for submerging the 105 entire craft.

Each member 23 is of novel construction. It embodies two parallel longitudinal side walls 30, a forwardly inclined top 31 of open-work form, a front 32 also of openwork con- 110

struction, and a plurality of flaps 33 pivotally hung at 34 and capable of jointly closing all openings in the top and front 31—32, as indicated by dotted lines in Fig. 5. As the member 23 moves upwardly in air, the flaps 33 open and such upward movement is hence unresisted to a large extent. Upon forward and downward movement of member 23 however, the flaps 33 automatically close, thus trapping air in the member 23 and causing the latter to exert a sustaining and propelling force. This same action takes place when the members 23 are positioned approximately as in Figs. 1 and 2, with the craft used in water. When members 23 are inverted however, as in Fig. 6, the flaps open upon downward movement of said members and close upon upward movement thereof, so that submerging of the craft may be attained.

When flying, after sufficient speed has been attained, the craft may be used as a glider. When this is done, the flaps 33 at the front of the member 23 merely swing rearwardly to substantially horizontal positions, permitting air to enter. At the same time, the remaining flaps 33 swing upwardly and rearwardly against the top 31, thus forming a weight-sustaining plane. Preferably, the top 31 has a sufficient curvature to simulate the curvature of the planes of an ordinary aircraft, to produce weight-sustaining.

From the foregoing, taken in connection with the accompanying drawings, the construction and operation of the craft will be readily understood without requiring more extended explanation, but it may be stated in conclusion that within the scope of the invention as claimed, numerous variations may be made and the present disclosure is for illustrative purposes only.

I claim:

1. A combined air and water craft comprising a combined fuselage and hull, and propelling means carried by said combined fuselage and hull for acting against either air or water to propel the craft, said propelling means embodying means for sustaining the weight of the craft when in the air and for submerging the same when in water upon adjustment of said means to a predetermined relation with said combined fuselage and hull, and means for so adjusting said propelling means.
2. In a craft, a body; a combined propelling and sustaining member carried thereby

and comprising longitudinal side walls, a forwardly inclined top, a front, said top and front having openings, and pivotally hung flaps for closing said openings; and driving means for moving said member forwardly, downwardly, rearwardly and upwardly; the flap or flaps at the front of said member being adapted to swing rearwardly when gliding, permitting air to swing the other flaps against the top to form a plane.

3. In a craft, a body, a transverse driven shaft mounted thereon and having a crank, an elongated downwardly-cupped propelling member having bearing means through which said crank passes, a longitudinal rod at one side of said propelling member, and means slidably and pivotally connecting the rear end of said member with said rod.

4. A structure as specified in claim 3; together with means for moving said rod vertically into different angular relations with said body.

5. In a craft, a body, a transverse driven shaft mounted on said body and having a crank, an elongated downwardly-cupped propelling member having bearing means through which said crank passes, a longitudinal rod at one side of said propelling member, a second transverse shaft mounted on said body and fixed to said rod for swinging the latter vertically to different positions, and means for turning said second shaft to different positions and holding it in any position to which it is adjusted.

6. A structure as specified in claim 5; said second transverse shaft being of tubular form and rotatably surrounding the first named shaft.

7. In a craft, a body, elongated downwardly cupped propelling members at opposite sides of said body, driving means pivotally connected with said members for moving said members forwardly, downwardly, rearwardly and upwardly, and manually controlled means for swinging said members about their pivotal connections with said driving means into different angular relations with said body.

8. A structure as specified in claim 7; the swinging means for either of said members being operable independently of the swinging means of the other member when desired.

In testimony whereof I have hereunto affixed my signature.

JOHN GRIFFIN.
